ABSORBENT ROLL AND METHOD OF
PRODUCING SAME

Emanuel R. Nelson, Glendale, and Nat Thompson,
Eagle Rock, Calif., assignors, by direct and
mesne assignments, to Johnson and Johnson, a
corporation of New Jersey

Application June 17, 1932, Serial No. 617,746

1 Claim. (Cl. 32—33)

Our invention relates to an absorbent roll and method of producing same and has for its principal object, the provision of a relatively simple, practical and inexpensive roll or pad that is composed of fibrous absorbent material such as cellulose, cotton or the like and which roll is especially adapted for use during dental operations, for the purpose of absorbing saliva and preventing the same from reaching that particular area of the patient's mouth that is being operated upon.

A further object of our invention is, to provide a relatively simple, inexpensive and easily practiced method for producing the absorbent rolls in elongated or practically continuous sections that may be conveniently packed or stored in suitable containers and cut off by the dentist in sections of usable length.

A further object of our invention is, to provide an absorbent roll of the character referred to, wherein a substantially cylindrical body of highly absorbent cellulosic material is enclosed within a casing or wrapper of fabric, preferably gauze and which casing is provided with internally arranged projecting portions that engage and intermingle with the fibers of the cellulosic filler, so as to effectually prevent relative longitudinal movement between the filler and casing when the absorbent roll is cut off in sections and used by the dentist for absorbing saliva during dental operations and treatment.

With the foregoing and other objects in view our invention consists in certain novel features of construction and arrangements of parts that will be hereinafter more fully described and claimed and illustrated in the accompanying drawing in which:

Fig. 1 is a perspective view of an absorbent roll embodying our invention and constructed in accordance with our method.

Fig. 2 is a perspective view of a short section of the fibrous or cellulosic body that forms the filler of the roll.

Fig. 3 is a cross section of the fabric casing or wrapper of the roll before the filler has been inserted therein.

Fig. 4 is an enlarged cross section taken on the line 4—4 of Fig. 1.

Fig. 5 is a diagrammatic view partly in section of a relatively simple form of apparatus that may be used in practicing our improved method.

Fig. 6 is an enlarged cross section taken on the line 6—6 of Fig. 5.

Fig. 7 is an enlarged cross section taken on the line 7—7 of Fig. 5.

The absorbent roll produced in accordance with our improved method comprises a filler body 10 of highly absorbent fibrous cellulosic material, which body is slightly compressed and given a cylindrical shape and after so shaped the cylindrical filler is inserted into a tubular casing or jacket 11 of fabric, preferably gauze, and which latter has been treated so as to render it antiseptic.

In the production of our improved roll, a relatively narrow strip of fibrous cellulosic material as illustrated in Fig. 1 is stitched lengthwise on a medial line as designated by 12 and this row of stitching, which is relatively loose, serves as a binder for the fiber of the strip and prevents said strip from disintegrating or spreading while being handled, shaped and inserted in the fabric tube that forms the casing of the roll.

This strip of cellulosic material, after being loosely stitched lengthwise as just described, passes through a former 13 that rolls the edges of the strip inwardly toward each other so as to give the strip cylindrical shape as designated by 14.

An elongated strip of fabric, preferably gauze, and which is mounted on a suitable support 15, preferably a spool, passes through a guide 16, and by said guide, the strip of gauze is caused to assume a substantially tubular form so as to enclose a tube 17 that extends through said guide.

After passing through the guide 16 and onto the end of the tube 17 that projects into said guide, the edges of the gauze are brought together and by means of a thread carrying needle 18, the projecting edges of the gauze are stitched to each other, thus forming a tube of gauze with the edges thereof projecting beyond the line of stitching.

The gauze tube now enters the end of tube 17 and moves lengthwise therethrough in a direction opposite to the direction in which the gauze moves through the guide 16 and thus the gauze tube is turned inside out.

In practice we prefer to locate the end of tube 17 adjacent to the discharge end of former 13 so that the cylindrical body of cellulosic material emerges from the end of the former and passes directly into the gauze tube as the latter is drawn through tube 17.

The edges of the strip of gauze used in forming the tube, project inwardly when the gauze tube is turned inside out, as just described, so that the projecting ends of the threads along said edges will engage and intermingle with the fibres in the cellulosic filler that passes into said tube.

gauze tube and as a result of this intermingling engagement, the gauze casing or wrapper and the filler of cellulosic material are prevented from readily moving lengthwise relative to each other 5 while being handled or cut into sections and while positioned within a patient's mouth during dental operations.

In this connection it will be understood that the 10 gauze is loosely woven from threads of vegetable fiber preferably cotton and that said threads have a much greater degree of stiffness and resiliency than the fibers of the cellulosic filler and as a result of this difference in stiffness and resiliency, the ends of the threads along the edges 15 of the gauze strip will press into and enter the body of the cellulosic filler so as to commingle with the fibers thereof.

After emerging from the tube 17, the roll composed of the filler body of cellulosic material enclosed 20 within the casing of gauze, passes onto the overrunning portion of a belt 19 that is mounted for operation on pulleys 20 and the width of which belt is approximately equal to the circumference of the roll.

The overrunning portion of belt 19 passes 25 through a longitudinally disposed tube 21, and in so doing the side portions of the belt are caused to flex upwardly so as to practically enclose the roll that is carried by said belt and this action 30 of causing the belt to surround the roll slightly compresses the same so that the diameter of the finished roll after passing off the belt is slightly less than the diameter of the roll that is formed in tube 17.

Other forms of apparatus may be utilized for 35 producing the absorbent roll in accordance with our method, but tests and experiments have proven that excellent results and a satisfactory product may be produced by the use of an apparatus such as is herein illustrated and described, 40 for with such apparatus, practically continuous lengths of rolls may be rapidly and economically produced and the rolls, after discharging from the belt 19, may be packed in suitable containers 45 for distribution and use.

In some instances it may be found desirable to cut the elongated roll as it comes from the forming apparatus, into sections of suitable length and which sections may be suitably packed for

delivery directly to the dentists or to the persons using the absorbent rolls in their work.

Absorbent rolls constructed in accordance with our improved method and made in larger sizes 5 may be advantageously employed as surgical dressings.

The friction between the overrunning portion of belt 19 and the enclosed roll is sufficient to unwind the strip of gauze from its spool or support 15 and to draw said gauze strip through the 10 guide 16 and thence in the reverse direction through tube 17 and to also pull the filler of cellulosic material through the former 13 into the gauze tube, as the latter is turned inside out.

While we have referred to the casing 11 as being formed of fabric such as gauze, it will be understood that our invention contemplates any other suitable casing of soft, flexible absorbent material, either knit or braided.

Thus it will be seen that we have provided a 20 relatively simple and easily practiced method for producing an absorbent dental roll that is composed of a filler of cellulosic material enclosed within a casing of fabric and the body of the 25 filler being stitched lengthwise to maintain the fibers in said body in proper position and portions of the filler and the fabric casing being intermingled so as to prevent relative longitudinal movement between said filler and casing while the 30 roll is being cut into sections and while the sections are positioned in the patient's mouth.

We claim as our invention:

The herein described method of forming an absorbent roll, consisting in delivering a sheet 35 of fabric from a source of supply, shaping such sheet into a tubular form while the sheet is moving in one direction, reversing the direction of travel of the tubular form to turn the same inside out, forming a roll of absorbent material immediately adjacent the point of reversal of 40 the tubular form with the diameter of the roll approximating the diameter of the reversed tubular form, delivering the roll into the reversed form, and subjecting the combined roll and form to a compressive shaping and feeding pressure, 45 to compress the completed article in desired shape.

EMANUEL R. NELSON.
NAT THOMPSON.
